(57) CLAIM

The ornamental design for a sports jersey dress, as shown and described.

DESCRIPTION

FIG. 1 is a perspective view of a sports jersey dress;

FIG. 2 is a first side view thereof;

FIG. 3 is a second side view thereof;

FIG. 4 is a third side view thereof;

FIG. 5 is a fourth side view thereof;

FIG. 6 is a top side view thereof;

FIG. 7 is a bottom side view thereof; and,

FIG. 8 is a cross-sectional view thereof.

The broken lines in the drawings represent stitching on the sports jersey dress that forms no part of the claimed design.

1 Claim, 6 Drawing Sheets
